UNITED STATES PATENT OFFICE.

CARL W. OMAN, OF SOUTH WINDHAM, CONNECTICUT, ASSIGNOR TO THE SMITH & WINCHESTER MFG. CO., OF SOUTH WINDHAM, CONNECTICUT, A CORPORATION OF CONNECTICUT.

REGISTRY DEVICE FOR BAG-MAKING MACHINERY.

Application filed April 18, 1924. Serial No. 707,445.

To all whom it may concern:

Be it known that I, CARL W. OMAN, a citizen of the United States of America, residing at South Windham, in the county 5 of Windham and State of Connecticut, have invented certain new and useful Improvements in Registry Devices for Bag-Making Machinery, of which the following is a specification.

10 My invention relates to a registry device for bag making machinery, and particularly to means for properly synchronizing the operation of related machine elements mounted on different shafts. While the invention 15 is applicable at various points to bag machinery, it is of particular value for synchronizing the operation of the rotary thumb-lip and cut-off knives of a bag tuber, so that they may be readily and accurately 20 correlated on an acceleration or retardation of the paper feed for the manufacture of bags of different lengths.

In the accompanying drawings, which illustrate a convenient embodiment of my invention in a tuber,

25 Fig. 1 is a broken longitudinal side elevation of a tuber of the well known Smith and Winchester type, to which my invention is applied, although it will be understood that by proper modification it may be embodied in tubers of other make;

30 Fig. 2 is a section on the line 2—2, Fig. 1;

Fig. 3 is a perspective of the thumb-lip knife drawn to a larger scale;

35 Fig. 4 is a fragmentary transverse section through the thumb-lip knife shaft and certain related parts drawn to a larger scale;

40 Fig. 5 is an end elevation of said shaft showing drive connections and of the registry device;

Fig. 6 is a section on the line 6—6, Fig. 5, drawn to a larger scale;

45 Figs. 7 and 8 are diagrams illustrating the course of the paper web through the tuber; and

Fig. 9 is a plan view of the tube after passing the cut-off knife.

50 In its main features the tuber in which my invention is here illustrated is of established type. It comprises a main frame 15

having at one end appropriate means for supporting the roll of paper 16 from which the tubes are formed. The web 17 is led from the roll over idlers 18, 19 and 20 to 55 the bed roll 21, upon which it is engaged by the thumb-lip knife 22 on the shaft 23 to form the thumb-lips or tabs 24. The web thus pierced at intervals, passes the folders 25 and 26 and in its now tubular form, is 60 engaged by the drawing rolls 27 which feed the tube to the cut-off knives 28—29 by which the tube is severed into the lengths desired for bags of different sizes.

The drive of all of the elements of the machine is taken from the pulley shaft 30, and it may be stated generally that the thumb-lip knife shaft and the cut-off knife shaft rotate at constant and equal speed (assuming the drive to be constant) for all lengths 65 of tubes, and that the variation in tube length is secured by varying the speed of the draw rolls 27 to accelerate or retard the feed of the paper through the machine. It is obvious from an inspection of the diagrams, Figs. 7 and 8, that upon a change 70 of speed of the feed rolls, the cut in the paper web by the thumb-lip knife will no longer register with the cut made by the cut-off knife. Since this registry is essential, adjustment of one or the other of the knives must be made to properly correlate the cuts. This I accomplish by the rotary 75 adjustment of the thumb lip knife with respect to its driving gear. Secondly, I provide a radial adjustment of the knife with respect to its shaft, so that the peripheral or linear speed of the knife may be made to substantially correspond to the altered speed of the web and thus prevent tearing 80 of the web by the knife at the moment of the lip cut.

The drive of the various parts will be readily followed from Figs. 1, 2 and 5. Thus, the draw rolls 27 are driven from the 85 pulley shaft 30 through gears 31, 32, 33, 34 and 35, the intermeshing gears 34 and 35 being mounted permanently on the draw roll shafts. Gear 33 which is also on draw roll shaft 36, and its meshing gear 32, are 90 both removable, and are substituted by others when it is desired to vary the speed

of the draw rolls, and thus the rate at which the web is passed through the tuber to change the length of the bag tubes.

For the sake of clarity, the gearing (well known) by which the cut-off knives 28 and 29 are driven from the pulley shaft 30, is not illustrated.

The drive of the thumb-lip knife shaft 23 is also taken from the pulley shaft 30 through bevel gear 37 which meshes with bevel gear 38 at one end of the inclined coupling shaft 39. At the other end of the latter the bevel gear 40 drives bevel gear 41, the gear 42 on which meshes with idler gear 43, and the latter with gear 44 on the shaft 23 of the thumb-lip knife.

While the drive of the thumb-lip knife is thus at a constant predetermined speed, corresponding to that of the cut-off knives 28-29, I provide means for varying both the angular relation thereof to its driving gear 44 and also its radial position with respect to its shaft 23.

To guide the attendant in making the radial adjustment of the knife, I mount a scale 45 in definite position upon the shaft 23 adjacent the T-bearing 47, of which surrounds the shaft 23. The scale 45 is graduated, and opposite the graduations are legends 48 which indicate bag lengths. The thumb-lip knife 22 is carried by a bar 49 resting against a flat 50 formed in the shaft 23 adjacent the T-bearing 47, and to which the bar 49 is clamped by the stirrup 51, if, for instance, change from a bag of 18" in length to a bag 36" in length be desired, the radial position of the knife 22 with respect to its shaft 23 is changed until it registers with the legend 36 on the scale 45, the bearings for shaft 23 being also shifted in guide frame 52 by means of an adjusting screw 53 (Fig. 1), until the shaft is properly located to bring the knife 22 into proper working relation with the bed roll 21. The increased linear speed of the rotary knife incident to the increase of its radius, now substantially corresponds to the increased speed of the web and prevents tearing of the web by the knife as it makes the lip cut.

To change the relative angular position of the shaft 23 with respect to its drive gear 44, and thus to synchronize the operation of thumb-lip knife 22 with the cut-off knives 28 and 29, the gear 44 is mounted on the shaft 23 by means of a cone clutch 54 fast on the shaft 23, and on which the gear is normally held fast by the clamp nut 55. Upon loosening the nut 55 the gear 44 can be sufficiently withdrawn from the cone 54 to permit the shaft 23 to be turned by hand. I also mount on the inner end of the clutch cone a dial 56, appropriately graduated around its circumference and with which cooperates a pointer 57 secured to the inner face of the gear 44. An associated chart

58, mounted for example on the head frame 59, advises the attendant as to the proper position of the pointer 57 on the dial 56 for a bag of definite length. Consequently, by setting the pointer 57 at the point on the dial 56 indicated by the chart, for a bag length of 36", exact synchronism of the thumb-lip knife 22 and cut-off knife 28 is obtained.

The radial adjustment of the thumb-lip knife 22 and of the gear 44 are both readily effected with precision by even an unskilled attendant. There is the least possible loss of time and no waste of paper such as is now common in the cut-and-try procedure heretofore practiced.

In connection with the adjustment of the shaft 23 toward and from the axis of the bed roll 21, by means of the hand screw 53, the mesh between gear 44 on the knife shaft, intermediate idler gear 43 and driving gear 42, is automatically maintained as follows. The intermediate gear 43 is mounted on a stud 60 which plays freely in the arcuate guide slot 61 in the head frame 59. Its proper location in the slot to insure the mesh of the gear 43 with gears 42 and 44 is determined by the links 62 and 63, of which the link 62 is mounted freely on the stud 64 of gear 42, while the other link 63 is mounted freely on shaft 23 of gear 44. Bosses at the opposite ends of the links form journals for the stud 60 on opposite sides of the head frame 59, and thus form a floating support for the stud. Obviously, as the shaft 23 is adjusted toward or from the bed roll 21, the links 62, 63 change their angular relationship and automatically shift the position of the gear 43 relatively to the gears 42 and 44, while positively maintaining it in meshing engagement.

While I have described my invention as applied to a tuber, it will be understood that it may be applied to other shafts or rotors of the machine which are relatively adjustable but must be synchronized in their operation. With this understanding that the construction shown is but an illustrative embodiment of what I claim as my invention, and the further understanding that the particular details of construction may be readily modified while accomplishing like results, I claim:

1. In a paper bag machine, a pair of rotary shafts, knives thereon adapted to effect related cuts in a paper web the speed of travel of which through the machine, may be varied and registry means for facilitating the adjustment of the relative position of the knives to synchronize their action upon variation of the feed of the web through the machine.

2. In a paper bag machine of the variable speed paper-feed type, a thumb-lip knife, a shaft on which the knife is mounted, a

scale mounted in fixed position adjacent the plane of travel of the knife, and means for adjusting the knife with respect to the scale to vary its radius and thus correlate its linear speed to that of the paper web.

3. In a paper bag machine, a thumb-lip knife, a rotary shaft on which the knife is mounted, a clutch member fast on the shaft, a driving gear adjustably mounted on the 10 clutch, and cooperating pointer and dial carried by said gear and clutch respectively for locating with exactitude the relative rotary position of the gear and shaft for the purpose set forth.

15 4. In a paper bag machine, a thumb-lip knife, a rotary shaft on which the knife is mounted, means for adjusting the knife on the shaft at various distances from the axis of the shaft, means for adjusting the shaft 20 toward and from the paper web, a gear adjustably mounted at one end of the shaft, a driving gear operatively associated with said gear on the shaft, and registry means 25 for exactly determining the relative rotary position of the gear-driven shaft with respect to the driving gear.

5. A registry device for synchronizing related shafts of a bag making machine or the like, one of said shafts having a gear thereon for driving the shaft, and a clutch connection between the gear and shaft, said registry device comprising a graduated dial carried by one element of the clutch, and a pointer carried by the other element of the clutch, and means for locking the clutch 30 parts in the relative rotary position indicated by the pointer on the dial.

6. In a paper bag machine, a pair of rotary cutters arranged on spaced axes, means for passing a flat web to one of said knives 40 to effect a cut therein, means for folding said flat cut web before it reaches the second knife, and means for severing the folded web at said second knife, together with registering means for facilitating the adjustment of the relative position of the knives to synchronize their action upon change of speed of the feed of the web 45 through the machine.

In testimony whereof I have signed my 50 name to this specification.

CARL W. OMAN.
